UNITED STATES PATENT OFFICE

2,508,033

REGENERATIVE FURNACE

Samuel S. Kistler, West Boylston, Mass., assignor
to Norton Company, Worcester, Mass., a corpo-
ration of Massachusetts

Application March 17, 1948, Serial No. 15,382

7 Claims. (Cl. 263—15)

1

The invention relates to furnaces and contem-
plates a built-in regenerator.

One object of the invention is to provide a
furnace with a built-in regenerator having low
resistance to passage of air. Another object of
the invention is to provide a compact apparatus
of the character indicated. Another object of the
invention is to provide a simple and easily con-
structed furnace apparatus of the type indicated.
Another object is to provide a furnace with built-
in regenerator, the mechanical parts of which are
readily accessible. Another object of the invention
is to provide a furnace with built-in regen-
erator of a revolving type which requires little
mechanical power to operate.

Other objects will be in part obvious or in part
pointed out hereinafter.

The invention accordingly consists in the fea-
tures of construction, combinations of elements,
and arrangements of parts as will be exemplified
in the structure to be hereinafter described, and
the scope of the application of which will be in-
dicated in the following claims.

In the accompanying drawings in which is
shown one of various possible embodiments of
the mechanical features of this invention,

Figure 1 is a sectional view of a furnace con-
structed in accordance with the invention, the
section being taken generally along the line 1—1
of Figure 3.

Figure 2 is an elevation of the fuel and air
distributing mechanism looking in the direction
of the arrows 2—2 of Figure 1.

Figure 3 is a horizontal sectional view on an
enlarged scale taken on the line 3—3 of Fig-
ure 1.

Figure 4 is a sectional view of the fuel valve
on a further enlarged scale taken on the line
4—4 of Figure 3.

Figures 5 and 6 are vertical axial sectional
views of the valve of Figure 4 looking in the
direction of the arrows 5—5 and 6—6 respec-
tively.

Figure 7 is a vertical sectional view on enlarged
scale of the distributor which appears near the
middle of Figure 4.

Figure 8 is a horizontal sectional view on an
enlarged scale and looking upward along the line
8—8 of Figure 1.

Figure 9 is a fragmentary enlarged detail of the
regenerator element of Figure 8.

Referring first to Figure 1, the furnace may
be mounted on a base plate 10 made of iron or
steel to which are attached four posts 11, likewise
of iron or steel, supporting an iron or steel plate
12. Upon the plate 12 is constructed an arch
13 of refractory material, for example made up
of two courses of bricks as shown. One end of
the arch 13 is more or less permanently blocked
by an end wall 14 made of brick, while, as shown

in Figure 3, the other or front end is blocked by
a brick wall 15 the upper part or some portion
of the upper part thereof being removable in
order to gain access to the ware when the fur-
nace is shut down. The base 10 is approximately
5 square, the plate 12 is approximately square and
as shown in Figure 2 the two sides of the arch
13 plus the back wall 14 and the front wall 15
form a more or less square enclosure. However,
10 within the scope of the invention other shapes
could be adopted. The shape shown has the ad-
vantage that it is easy to construct and to re-
pair and it is easy to remove and replace the
front wall 15. At the same time the arch 13
15 and the walls 14 and 15 provide a semi-cylin-
drical space which is excellent from the point of
view of combustion and provides a large space for
setting the ware. That is to say, the gases of
20 combustion go up and down along the inside of
the arch 13 and provide radiant heat to all sides
and the top of the ware which should be set in
the central part of the chamber.

Referring again to Figure 1, approximately in
the center of the plate 12 is a circular opening
25 which is closed at the under side by a cylin-
drical box 21 made of steel suitably secured to
the under side of the plate 12. Over the opening
20 is a refractory regenerator 25 which is dis-
closed more in detail in Figures 8 and 9 and which
30 will be hereinafter described. This regenerator
25 is shown as cylindrical in shape but it may
be of other shape so long as it covers the opening
20. Surrounding the regenerator 25 and between
the straight legs of the arch 13 and of the walls
14 and 15 is brick work 26 which may be sup-
plemented by cement wherever it is difficult to
make the bricks conform to the cylindrical sur-
face of the regenerator 25.

The top of the brick work 26 together with
the top of the regenerator 25 forms a flat top 29
over which pass incoming air and the outgoing
gases. Over this flat top 29 is located a refrac-
tory ware carrying plate 30 preferably made of
40 a single piece of vitrified refractory material such
as of silicon carbide bonded with vitrified clay
or other ceramic material. This plate 30 has on
the under side thereof ribs 31 in the form of a
cross the four portions of which are perpendicu-
lar to the surfaces of the arch 13 and of the walls
14 and 15 and meet the legs of the arch and
the walls 14 and 15 at midpoints thereof. The
plate 30 is likewise in contact with the legs of the
arch 13 and the end walls 14 and 15 and thus
the plate 30 and the ribs 31 in the form of a cross
divide the space between the under side of the
plate 30 and the surface 29 into four substan-
tially uniform compartments 32 which are ap-
proximately square in plan view and of moderate
depth. Air is constantly entering two or three
50 of these compartments 32 and thence through
the top 29 into the furnace.

holes 36 in the plate 30 entering the combustion chamber, and exhaust gases are constantly leaving by one or two holes 36 and one or two chambers 32. In coming air passes through the regenerator 25 in an upward direction and exhaust gases pass through the regenerator 25 in a downward direction. The portions of the regenerator 25 through which the air on the one hand rises and the exhaust gases on the other hand descend is ever varying as will presently be made clear.

Referring now to Figures 1 and 7, through the bottom of the box 21 extends the straight portion of a large air pipe 39 which is curved below the box 21 as shown in Figure 1 and which is connected to a suitable blower 40 providing a large volume of air under low pressure. Referring now to Figure 7, the pipe 39 may be secured to the bottom of the box 21 and sealed to the opening 41 therein through which it passes by means of a ring 42 welded to the bottom of the box 21 and having a beveled face 43 against which a soft metal ring 44 is pressed by a ring 45 secured to the ring 42 by means of bolts 46. The soft ring 44 contacts the pipe 40 as shown in Figure 7.

Extending through the curved portion of the pipe 39 as shown in Figure 1 is a sleeve 47 through which extends a vertical shaft 48 that is constantly rotated at a slow rate of speed by mechanism to be hereinafter described. Referring now to Figure 7, secured to the top of the shaft 48 is a spider 50 comprising a hub 51, arms 52 and a cylindrical ring 53 which rests on top of the pipe 39. A sleeve 54 is secured by set screws 55 to the ring 53 and the sleeve 54 projects downwardly and surrounds the upper part of the pipe 39 thus to keep the spider 50 centered on the pipe 39. Referring to Figures 1, 7 and 8, welded to the upper edge of the cylindrical ring 53 all the way around it is a distributor 60 which includes a semi-circular flat plate 61 with a semi-circular cut-out the edge of which is welded to the ring 53, a semi-circular shaped part 62 the bottom of which is welded to the remainder of the ring 53, a diametral vertical wall 63 welded to the part 62 and a semi-circular vertical wall 64 welded to the flat plate 61. The walls 63 and 64 practically touch the under side of the regenerator 25 and as the distributor 60 revolves it delivers air to a constantly changing half of the regenerator 25.

Referring now to Figures 8 and 9, the regenerator 25 is preferably made up of a great number of hexagonal rods 65 of refractory material. Each rod 65 has a number of bores 66 extending therethrough; illustratively there may be seven bores 66 arranged as shown in Figure 9 to provide a large total interior surface area. These rods 65 may be made by extruding ceramic material and then vitrifying it. The hexagonal shapes permit close compacting of the rods as shown in Figure 9; the periphery of the entire mass is shaved before firing in order to make the regenerator cylindrical and any resultant grooves may be filled in with cement as shown at 67. The firing is preferably done after the "green" rods 65 have been assembled and pressed together; after firing there is provided a cylindrical regenerator block having a great number of holes 66 parallel to its cylindrical axis and well distributed throughout the mass. This regenerator block 25 is not only refractory but capable of absorbing and holding a great number of British thermal units or calories, that is to say a large quantity of heat. After the furnace has been

operating for one-half revolution of the distributor 60, heat is imparted by the hot regenerator to the incoming cold air which is delivered by the pipe 39; at the same time the volume of the regenerator block 25 whose under surface is not within the area of the distributor 60 is acquiring heat from the hot exhaust gases. These hot exhaust gases enter the box 21 (but at a lower temperature than that at which they enter the regenerator 25) and are conducted to a chimney or stack by means of a large pipe 70 connected to the box 21.

Referring now to Figures 2 and 8, mounted on the base plate 10 is an electric motor 75 having a stepped pulley 76 any groove of which may be connected by means of a belt 77 to the opposite groove of a stepped pulley 78 mounted on a shaft 79 of a speed reduction mechanism 80. This speed reduction mechanism 80 has an output shaft 81 upon which is mounted a bevel gear 82. Any type of speed reducing mechanism may be used which gives the desired ratio, and many types are on the market. Accordingly, since reducing gearing is a separate art, it is not deemed necessary to illustrate the details of such speed reducing mechanism herein. In the present case a mechanism 80 was selected which had a ratio of 900 to 1, that is to say for every 900 revolutions of the shaft 79, the shaft 81 revolved once. The gear 82 meshes with a bevel gear 83 which is on the lower end of the shaft 48. Since the diameter of the largest groove of each of the pulleys 76 and 78 is about twice the diameter of the smallest groove thereof, and since the bevel gears 82 and 83 have the same diameter, it takes between 450 and 1800 revolutions of the pulley 76 to produce one revolution of the shaft 48 and therefore of the distributor 60. The motor 75 was rated 1725 R. P. M. Therefore the distributor 60 may be made to rotate as slowly as once in every sixty-two and one-half seconds or as fast as once in every fifteen and seven-tenths seconds. The distributor 60 can also be rotated at two other speeds intermediate these limits with pulleys 76 and 78 having four steps as shown. Obviously, in accordance with the invention other ratios and speeds can be adopted.

The sleeve 47 as best shown in Figures 1 and 2 is supported by a plate 85 in the nature of a table which has three legs 86 supported by the base 10. Thus the shaft 48 and the bevel gear 83 are supported and journaled. Meshing with the bevel gear 83 is an equal sized bevel gear 90 on the end of a shaft 91 of a fuel valve generally designated by the numeral 92.

Referring now to Figure 1, a fuel pipe 93 conducts fuel such as a combustible gas to the valve 92. Referring now to Figure 5, the valve 92 comprises a main octagonal casing 95 having legs 96 by means of which it may be bolted to the base plate 10. The casing 95 has a cylindrical bore 97 straight through it, the bore having a horizontal axis. Integral with the shaft 91 is a cylindrical portion 98 closely fitting the bore 97. Integral with the cylindrical portion 98 is a hollow semi-cylindrical portion 99 whose outer cylindrical surface likewise closely fits the bore 97. Integral with the hollow semi-cylindrical portion 99 is a hollow fully-cylindrical portion 100 whose outer cylindrical surface also closely fits the bore 97. These portions 98, 99 and 100 constitute a revolving valve. Attached to one end of the cylindrical casing 95 by means of bolts 101 extending through a flange 102 thereof is a hollow cylindrical member 103 having a bore 104 of somewhat

less diameter than that of the bore 97. This member 103 is blocked at the right hand end, Figure 5, by a long hub 105 having a small internally threaded bore 106. The fuel pipe 93 is connected to the hollow cylindrical member 103 outside of an orifice 110 through which gas or other fuel enters the valve 92. The gas has no outlet from the member 103 except through the wide bore 111 in the portion 108.

Referring now to Figure 4, it will be seen that the semi-cylindrical portion 99 always blocks one half of the circle of the casing bore 97 between the portions 98 and 100. Four large fuel ports 115, 116, 117 and 118 extend through the casing 95 and into the bore 97 between the portions 98 and 100. It will be seen that as the semi-cylindrical portion 99 rotates, two and sometimes three of these ports are open while sometimes two and sometimes only one of these ports are closed. Connected to the ports 115, 116, 117 and 118 are threaded pipe ends 119, 120, 121 and 122. Thus gas from the port 110 is directed to two or three of these pipe ends.

Comparing now Figures 1, 3 and 4, the pipe end 119 is on an angle union 123 which is connected to a pipe 124 which is connected to a right angle union 125 which is connected to an outside pipe 126 which is connected to a right angle union 127 which is connected to a horizontal pipe 128 which extends through the left hand leg of the arch 13 and terminates right under one of the holes 36 in the plate 30. Similarly, the pipe end 122 is on the end of an angle union 130 which is connected to a pipe 131 which is connected to a right angle union 132 which is connected to a pipe 133 which is connected to a right angle union 134 which is connected to a horizontal pipe 135 which extends through the right hand leg of the arch 13 and terminates just under another hole 36 in the plate 30. The pipe end 120 is on the end of a pipe 140 which is connected to an angle union (not shown) which is connected to a pipe (not shown) which is connected to a right angle union (not shown) which is connected to a horizontal pipe 145 extending through the left hand leg of the arch 13 and terminates just under a hole 36 through the plate 30. Likewise the pipe end 121 is on the end of a pipe 150 which is connected to an angle union (not shown) which is connected to a pipe (not shown) which is connected to a horizontal pipe 155 which extends through the right hand leg of the arch 13 and terminates just under a hole 36 in the plate 30. Each of the pipes 128, 135, 145, and 155 is plugged at the inner end and has near such end a hole in the top, numbered respectively 156, 157, 158 and 159 in Figure 3, to direct gas through the corresponding hole 36. In the position of the semi-cylindrical portion 99 shown in Figure 4, gas is flowing through the pipes 145 and 128. In the position of the distributor 60 as shown in Figure 1, air is flowing through the chambers 32 which have the holes 36 adjacent these same pipes.

Referring again to Figure 5, the left hand end of the casing 95 is blocked by a plate 160 fastened to the casing by bolts 161. The shaft 91 extends through a bore 162 in this plate 160 and a suitable seal 163 in a countersunk portion 164 helps to prevent gas from escaping. I preferably provide means to control the flow of fuel gas and preferably without reducing the pressure inside of valve 92. Referring now to Figures 4 and 6, I provide a slideable port covering valve member 170 which has a semi-cylindrical exterior surface 171 fitting the cylindrical surface 97. It likewise has

two diametral plane surfaces 172 which engage corresponding diametral plane surfaces 173 of the semi-cylindrical portion 99. Normally, when the valve is wide open, the valve member 170 is beyond the ports 115, 116, 117 and 118. It will be observed that the valve member 170 is shown in full lines in Figure 4. In Figure 5, which shows a section of the valve member 170, it is seen to be at the left hand end of the portion 99. Means is provided for drawing the sliding valve member 170 over the ports 115, 116, 117 and 118 more or less. To this end, as shown in Figures 5 and 6, I provide a shaft 175 having screw threads 176 engaging the internal threads 106 of the hub 105. To the outer end of the shaft 175 is secured a turning knob 177 by means of a pin 178. The inner end of the shaft 175 has a head 180 which is located in a bayonet slot 181 of the sliding valve member 170. In the position of the sliding valve member 170 shown in all the figures, the ports 115, etc. are fully open. But if the turning knob 177 is turned, the sliding valve member 170 will be moved, more or less, to cover more or less of the area of the ports 115, etc., up to complete closure thereof. In such a case of complete closure, the sliding valve member 170 would be in contact with the portion 100. The shaft 175 extends through a seal 185 in a countersunk portion 186 in the hub 105.

Thus, while the valve member represented by the portions 98, 99 and 100 is always rotating to change the distribution of the gas, the sliding valve member 170 is likewise rotating and may be manually adjusted to any position inside the valve 92 between a position where it does not obstruct the ports 115, etc. whatsoever and a position where it virtually closes them apart from slight leakage.

To lubricate the rotating members, I may provide channels 190, 191, 192, 193 and 194 in the casing 95 all as clearly shown in Figures 5 and 6. The entrance channel 194 for the oil may be sealed with a plug 195.

In order to load the furnace, access is gained to the chamber by removal of part or all of the front wall 15. Of course this wall 15 is removed at least in part at the completion of a vitrifying or other furnace operation for the removal of ware that has been vitrified or otherwise heat treated. Therefore the operator usually finds the front wall 15 entirely or partly missing, that is from the level of the plate 30 upward. His first job therefore is to set the "green" ware. This "green" ware is set or stacked upon the ware carrying plate 30 in accordance with principles known in the ceramic arts. That is to say, batts and saggers can be used if and as desired.

The furnace having thus been charged, the operator proceeds to rebuild the front wall 15. He does not necessarily use any mortar, although he may if he desires to do so. Two courses of bricks can be used and so located as to minimize movement of flame, gas or air through the wall. Two courses of bricks will adequately keep the heat from escaping from the furnace. In thus building up the wall, the operator will omit enough bricks to leave a small hand hole for lighting the furnace.

Referring now to Figure 1, it will be seen that the exhaust pipe 70 is connected to the inlet side of a centrifugal blower 200. This blower 200 has an exhaust channel 201 which is connected to piping 202 leading to a smoke stack in the building. The blower 40 has an inlet 203 which takes air from the room or from outdoors and dis-

charges it through a channel 205 which is connected to a curved pipe 206 which is connected to the pipe 39. Thus air is pumped into the furnace but by reason of the use of the exhaust blower 200, the pressure in the furnace chamber is or may be atmospheric. For this reason there will be no tendency of the gases to pass through the wall 15 which is not air tight, nor need there be any tendency for air to pass inward through the wall 15. I provide dampers 203 and 209 which may be of conventional type and which may be located in the pipes 206 and 70 respectively and by manipulation of these dampers, the operator can quickly check any indraft of air or exhaust of gases through the wall 15. That is to say, if air seems to be sucked into the furnace through the wall 15, turning of the damper 209 to check the exhaust slightly is indicated. Whereas, if gas is escaping outwardly through the wall 15, turning of the damper 208 to check the blast of air into the furnace is indicated.

To light the furnace, first see that the knob 177 is in such a position that the sliding valve member 170 will allow some gas to enter the furnace. Then pass a lighted torch of some nature through the hole in the wall 15 and locate the flame over one of the holes 36. The gas should now be turned on using a hand valve 210 in the pipe 93. The air should not be turned on yet. If the gas does not light, shift the torch or taper immediately to another hole 36 and so on until the gas does light. Immediately the gas has lighted, throw the switches for the two blowers 40 and 200 and then check the front wall 15 to see if the draft is in or out and neutralize the condition as above explained. Now the furnace is in operation and the intensity of the heat may be adjusted by turning the knob 177. At any time the remaining hole in the wall 15 may be plugged with bricks but perhaps it will be desired to leave it open for observation.

It will thus be seen that there has been provided by this invention a furnace with built-in regenerator in which the various objects hereinabove set forth together with many thoroughly practical advantages are successfully achieved. As many possible embodiments may be made of the above invention and as many changes might be made in the embodiment above set forth, it is to be understood that all matter hereinbefore set forth or shown in the accompanying drawings is to be interpreted as illustrative and not in a limiting sense.

I claim:

1. A regenerative furnace comprising a refractory structure forming a firing chamber, a refractory plate extending across the bottom of said chamber there being several compartments under said plate and holes through said plate from said compartments, a regenerator having a plurality of vertical passages under said plate communicating with said several compartments, a distributor under said regenerator formed to deliver air to some but not all of said passage at any given moment, means mounting said distributor for rotation whereby during the course of a revolution it delivers air through said passages to the compartments successively, means rotating said distributor, means delivering air to said distributor, rotary valve means, a pipe delivering fuel to said rotary valve means, pipes from said rotary valve means to positions adjacent the holes through said plate whereby to

deliver fuel to different portions of the chamber successively, and means to collect the gases of combustion exhausted through said regenerator from said firing chamber via said compartments.

5 2. In a regenerative furnace as claimed in claim 1, the combination with the parts and features therein specified, of means for blowing air into the distributor, and separate means to withdraw combustion gases from the regenerator, whereby the firing chamber can be caused to operate while combustion is taking place at atmospheric pressure thus obviating a requirement of tightly sealing the firing chamber.

10 3. In a regenerative furnace as claimed in claim 1, the combination with the parts and features therein specified, of ribs on the under side of the refractory plate forming the compartments.

15 4. A regenerative furnace comprising a refractory structure forming a firing chamber, a refractory structure forming horizontal passages under said chamber, there being a communication between each passage and said chamber, a regenerator having vertical passages under said horizontal passages whereby a plurality of vertical passages leads to each horizontal passage but no vertical passage leads to more than one of the horizontal passages, a box under the regenerator, connected to exhaust, a distributor in the box and open at any moment to some but not all of the vertical passages, an air pipe leading to the distributor through the box, and means to rotate the distributor.

20 5. In a regenerative furnace as claimed in claim 4, the combination with the parts and features therein specified, of rotary valve means and connections to deliver fuel to different parts of said firing chamber successively.

25 6. In a regenerative furnace as claimed in claim 5, the combination with the parts and features therein specified, of means to blow air into the distributor and separate means to suck gases out of the box, whereby the firing chamber can be caused to operate while combustion is taking place at atmospheric pressure thus obviating a requirement of tightly sealing the firing chamber.

30 7. A regenerative furnace comprising a refractory structure forming a firing chamber, a regenerator thereunder, connections including a rotary distributor to direct air successively through different portions of said regenerator to said chamber and to collect exhaust gases from said chamber successively through different portions of said regenerator, connections including a valve with a moving valve member to deliver fuel successively to different portions of said firing chamber, means for blowing air into the distributor, and separate means to withdraw combustion gases from the regenerator, whereby the firing chamber can be caused to operate while combustion is taking place at atmospheric pressure thus obviating a requirement of tightly sealing the firing chamber.
